HINGE

George Washington Henry, Westfield, Mass., assignor to Anderson & Sons, Inc., Westfield, Mass., a corporation of Massachusetts.

Application September 4, 1947, Serial No. 772,160

8 Claims. (CL. 33—115)

1

This invention relates to hinges.

An object of this invention is a compact and efficient hinge construction, adapted for a wide range of uses which can be simply made at low cost.

The hinge construction of this invention is useful for pivotally connecting two strips in such manner that the strips are impositively locked in one or more angular relations and is particularly adapted for use in a folding rule or the like. According to this invention, two strips may be hinged together without the use of any element other than the strips themselves and the hinge elements may, if desired, be formed by a stamping operation. The material and labor cost of producing such a hinge is, therefore, extremely low. Although the preferred use of the hinge construction of this invention is in folding rules, many other uses of it will be readily apparent.

Other objects, novel features and advantages of this invention will become apparent from the following specification and accompanying drawings, wherein:

Figure 1 is a plan view of one form of folding rule equipped with a hinge construction embodying the invention;

Fig. 2 is a section on the line 2—2 of Fig. 1; Fig. 3 is a view (similar to Fig. 1) of a modification;

Fig. 4 is a section on the line 4—4 of Fig. 3; Fig. 5 is a view similar to Fig. 2 of a further modification;

Fig. 6 is a section on the line 6—6 of Fig. 5; Fig. 7 is an enlarged plan view of one element of the hinge construction prior to assembly with the remaining elements; and

Figs. 8 and 9 are enlarged sections on the line 8—8 of Fig. 2, showing the hinge pintle in different positions.

The invention as disclosed herein is embodied in a hinged rule or scale which, in the embodiment of Figs. 1 and 2, is composed of two sheet metal strips 10 and 11. In one end of the strip 10 is cut a central longitudinal slot 12, thereby forming two prongs 10a, and opposed recesses 13 are formed in the adjacent prong faces near the outer end of the slot (see Figs. 8 and 9). The two recesses 13 define an aperture through which project two identical tongues or lugs 14 struck upwardly from the strip 11 in parallel relation, the ends of the tongues 14 projecting beyond the plate 10 being turned over the edges of the aperture. The spacing and dimensions of the tongues are such that the outer corners thereof define a square and the tongues constitute the hinge

5 pintle. The wall of each recess 13 is provided with two notches 15 in which, for certain relative angular positions of the strips 10 and 11, the outer corners of the tongues or lugs 14 are received (Fig. 8).

10 This arrangement interconnects the two strips 10 and 11 but permits relative rotation of the two strips about an axis centrally of the square defined by the two tongues or lugs 14. Upon relative rotation of the two strips, the edges of the tongues 14 move out of the notches 15 into engagement with the curved surfaces of the recesses 13, thereby slightly spreading apart the two prongs 10a of the strip 10. Each time the edges 15 of the tongues 14 come into alignment with the notches 15, the two prongs 10a spring together to impositively retain the two strips in said position. The arrangement of the notches 15 in the embodiment shown in Figs. 8 and 9 is such that the two strips are impositively held either in alignment with each other or at right angles to each other.

15 In the modification illustrated in Figs. 3 and 4, the hinged rule or scale is composed of two strips 20 and 21 of wood, plastic or other light-weight material. In the end of the strip 20 is embedded a short, thin sheet metal strip 10' while in the end of the strip 21 is embedded a short thin sheet metal strip 11'. Except for their dimensions, the metal strips 10' and 11' of this modification are identical with the metal strips 10 and 11 of the embodiment of Figs. 1 and 2 and they are interconnected in the same manner as described in connection with said modification. The two strips 10' and 11' which hinge together the strips 20 and 21 are positioned within recesses 25 formed in the strips 20, 21 and are attached thereto by suitable prongs or tabs 22, 23 respectively which are bent around their respective strips, thereby strengthening the elements. Sufficient clearance is provided to permit the spring action of the prongs 10a' and to permit rotation of tongues 14' within the recess formed in strips 20.

30 In the modification of Figs. 5 and 6, the strips 10 and 11 are interconnected by a solid square pintle 16 riveted to the strip 11 and extending through the strip 10 in the same manner as the tongues 14 of the modification of Figs. 1 and 2, said pintle being headed over onto the strip 10 to form a firm connection. The cross-section of the pintle 16 is of the same dimensions as the square defined by the outer corners of the tongues 14.

35 As shown in Fig. 7, each recess 13 is defined by

a central arc *a* extending between two notches *15* and two arcs *b* and *c* each extending from one notch *15* to the edge of the prong *10a*. These arcs should, preferably, be struck from different centers. In general, arc *a* is to serve as the bearing surface during movement of the hinged members from one to another position, and arcs *b* and *c* are to serve merely as guiding (but not bearing) surfaces during such movement. While actual dimensions, location of centers and radii of curvature depend in any particular case upon the thickness of metal used, the length of slot *12* and the elastic characteristics of the metal, one satisfactory arrangement of centers and radii is set forth below.

The arc *a* may be struck about a center *x* lying in a line *l-l* perpendicular to the center line *m-m* of the slot *12* and nearer the edge of the opposite prong *10a* than the edge of the prong in which the arc occurs. The arcs *b* and *c* may be struck respectively about centers *y* and *z* lying in a line *n-n* parallel to the line *m-m* and passing through the center *x*, the center *y* being slightly spaced from the center *x* in one direction and the center *z* being slightly spaced from the center *x* in the opposite direction. The junction of each arc *b* and *c* with a wall of the slot *12* lies approximately on the circumference of a circle having its diameter equal to the diagonal of the square defined by the outer corners of the tongues *14* and having its center at the intersection of the lines *l-l* and *m-m*. The notches *15* of each recess *13* are of proper shape and spacing to receive two corners of the square defined by the tongues *14*, while the distance between corresponding notches in the opposite recesses *13* is slightly less than the side of said square. The above described relationship is illustrated in Fig. 7 by indicating the tongues *14* in dotted lines on the upper face of the strip *10*.

As shown in Figs. 8 and 9, the two strips *10* and *11* are assembled by inserting the tongues *14* through the opening defined in the strip *10* by the notches *13* and bending over the tongues *14* as illustrated in Figs. 2 and 4. In order to effect this assembly of the two strips, the prongs *10a* are sprung apart slightly to space the corresponding notches of the opposite recesses *13* equal to the width of the tongues *14*, thus putting the prongs under tension which persists as long as the two strips *10* and *11* are maintained in assembled relation. The friction exerted between the strips *10* and *11* by reason of the tension in the prongs *10a* serves impositively to lock the corners of the tongues in the notches *15* when the two strips are in the position shown in Fig. 1 or in any one of three additional relatively angular positions in which the corners of the tongues *14* register with the notches *15*.

Upon relative rotation of the two strips from the position shown in Fig. 8 to the position shown in Fig. 9, each arc *a* is engaged by one tongue corner, thus increasing the spread of the prongs *10a* with corresponding increase of tension in the prongs. With the prongs *10a* at maximum spread, the centers *x* coincide with the intersection of the lines *l-l* and *m-m* while the centers *y* and *z* lie in the line *m-m*. Continued relative rotation of the two strips *10* and *11* brings the tongue corners again into register with notches *15* whereupon the prongs *10a* snap back to the position shown in Fig. 8 to again impositively lock the two strips.

In the modification of Figs. 5 and 6, the square cross-section pintle *16* cooperates with the

periphery of the recesses *13* and with the notches *15* in the same manner as the tongues *14*.

It is desirable in making the hinge of this invention that the tongues *14* or the square pintle *16*, be hardened so that the corners thereof will resist wear. The bearing surfaces of opening *13* may also be hardened.

While in the form of this invention which now appears to be preferable and most convenient, the notches *15* are so positioned in the arcuate walls of the recesses *13* as to define substantially the corners of a square, it is possible to place them at other positions and to provide any even number of such notches in excess of four. The purpose of the notches *15* is to define an angular position at which the hinged members will stop and be held. When there are four notches defining the corners of a square, the hinged members are stopped at 90° intervals of rotation. The notches can be placed at other positions as desired in order to permit the hinged members to be impositively held at other angular positions or at more than four such positions in each 360° of rotation. In such cases, the tongues *14* are shaped in such manner that their corners will engage any one or more of a pair of notches, each notch of a pair being diametrically opposed to the other notch of the same pair.

The above-described hinge construction is of such nature that the two strips *10* and *11* will not stick and the hinge will have a long effective life. All parts of the hinge are subjected to uniform tension and the two strips are snapped into open or closed position. There are no parts to get out of order and the rule will lie flat on a surface and not rock. The rule may be easily and quickly opened and closed and takes up but little pocket room.

While the invention is disclosed as embodied in a folding scale hinge, it may be utilized in hinge constructions for table leg brackets, box covers, step ladders, windows, drapery holders, electrical switches and for many other uses which will suggest themselves to persons skilled in the art. It is to be understood that such uses of the invention are intended to be comprehended by the appended claims and that the invention is limited only by the scope of such claims.

I claim:

1. A hinge construction comprising two strips, one of said strips being slotted to form two prongs, opposed arcuate recesses in the adjacent faces of said prongs, spaced depressions in the walls of said recesses, and lugs struck out from the other strip passing through said first strip and turned over into engagement with the surface thereof, the edges of said lugs being adapted to engage said depressions to maintain the strips in desired angular relationship and to be disengaged from said depressions against the spring action of said prongs when one strip is rotated relative to the other.

2. A hinge construction comprising two flat members of sheet metal, one of said members being slotted and having a circular perforation larger in diameter than the width of the slot and intercepting both sides thereof and having spaced depressions in the internal circular wall thereof, the other of said members having lugs struck out and penetrating said perforation with the edges of said lugs being adapted to engage said depressions to maintain the members in desired angular relationship and to be disengaged from said depressions against the spring action of the

5

slot when one member is rotated with respect to the other.

3. A hinge construction comprising two strips, one of said strips being slotted to form two prongs, opposed arcuate recesses in the adjacent faces of said prongs, spaced depressions in the walls of said recesses, and lugs struck out from the other strip passing through said first strip and turned over into engagement with the surface thereof, said lugs being of proper dimensions to spread said prongs apart under tension and the edges of said lugs being adapted to engage said depressions to maintain the strips in desired angular relationship and to be disengaged from said depressions against the spring action of said prongs when one strip is rotated relative to the other.

4. A hinge construction comprising two strips, one of said strips being slotted to form two prongs, opposed arcuate recesses in the adjacent faces of said prongs, spaced depressions in the walls of said recesses, a pintle carried by one of said strips and passing through said first strip in alignment with said recesses, said pintle having corners adapted to engage said depressions to maintain the strips in desired angular relation and to be disengaged from said depressions against the spring action of said prongs when one strip is rotated relative to the other.

5. A hinge construction comprising two flat members of sheet metal one of said members being slotted and having circular perforations larger in diameter than the width of the slot and intercepting both sides thereof and having spaced depressions in the internal circular wall thereof, the other of said members carrying a pintle penetrating said perforations and having corners adapted to engage said depressions to maintain the members in desired angular relationship by engagement with said depressions and to be disengaged from said depressions against the spring action of the slot when one member is rotated with respect to the other.

6. A hinge construction comprising two strips, one of said strips being slotted to form two prongs, opposed arcuate recesses in the adjacent faces of said prongs, spaced depressions in the walls of said recesses, and a pintle passing through said first

6

strip in alignment with said recesses and having corners for engagement in said depressions, said pintle being of proper dimensions to spread said prongs apart under tension and the corners of said pintle being adapted to engage said depressions to maintain the strips in desired angular relationship and to be disengaged from said depressions against the spring action of said prongs when the two strips are rotated relative to each other.

7. A hinge construction comprising two strips, one of said strips being slotted to form two prongs, opposed arcuate recesses in the adjacent faces of said prongs, spaced depressions in the walls of said recesses, each recess being defined by a main arc and two lateral arcs with a depression at the junction of each lateral arc with the main arc, said main arc being struck about a center which lies in a line in the plane of the strip at right angles to the center line of the slot and, in that line, is located between said center line and the slot edge opposite the recess, each lateral arc being struck about a center lying in a line in the plane of the strip which is parallel to the center line of the slot and lies between said center line and the said opposite slot edge, a square pintle extending from the other strip through the opening defined by said recesses, the two depressions in each recess wall being of proper size and spacing to receive the corner of the pintle and said prongs being spaced apart under tension to accommodate said pintle, the distance between corresponding depressions in opposite recesses being less than the pintle side when the prongs are free of tension.

8. A hinge construction according to claim 7, in which said pintle consists of two identical parallel lugs struck out from the second strip.

GEORGE WASHINGTON HENRY.
